UNITED STATES PATENT OFFICE

147,209

DESIGN FOR A THROTTLE TYPE FAUCET

Edward C. Wells, Seattle, Wash., assignor to Boeing Aircraft Company, Seattle, Wash., a corporation of Washington

Application February 7, 1946, Serial No. 126,369

Term of patent 14 years

(Cl. D91—3)

To all whom it may concern:

Be it known that I, Edward C. Wells, a citizen of the United States, residing at Seattle, in the county of King and State of Washington, have invented a new, original, and ornamental Design for a Throttle Type Faucet, of which the following is a specification, reference being had to the accompanying drawing, forming part thereof.

Figure 1 is a perspective view showing my new design.

Figure 2 is a front elevation view of such throttle type faucet, and Figure 3 is a side elevation view thereof.

I claim:

The ornamental design for a throttle type faucet, substantially as shown.

EDWARD C. WELLS.
